LUBRICATOR

Frank S. Barks, St. Louis, Mo.

Application August 8, 1934, Serial No. 738,954

5 Claims. (Cl. 308—80)

This invention relates to lubricators, and with regard to certain more specific features, to lubricators for journal boxes and the like.

Among the several objects of the invention may be noted the provision of an automatic, journal-box lubricator which is operable by the side sway induced by movement of the vehicle on which the device is located; the provision of such a lubricator which has lubricant available on the journal bearing surface at starting from a standstill; the provision of a device of the class described which materially reduces the starting friction of the journal to which it is applied; the provision of a device of this class described which more efficiently lubricates the journal while in motion; and the provision of apparatus of this class which shall confine the circulation of the lubricant to the lubricating system without substantial leakage. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which are illustrated two of various possible embodiments of the invention,

30 Fig. 1 is a vertical section showing the device applied to a locomotive journal;

Fig. 2 is a right side elevation of Fig. 1;

Fig. 3 is an enlarged longitudinal section taken through a pump;

35 Fig. 4 is a fragmentary plan view of parts of the pump shown in Fig. 3;

Fig. 5 is a bottom plan view of a crown brass bearing block;

Fig. 6 is a cross-section taken on line 6—6 of 40 Fig. 5;

Fig. 7 is a cross-section taken on line 7—7 of Fig. 5;

Fig. 8 is a plan view showing the arrangement of pumps in an alternative system for supplying lubricant to a longer journal; and,

Fig. 9 is an enlarged view similar to Fig. 5 but showing a long bearing block applicable to the structure of Fig. 8.

Similar reference characters indicate corresponding parts throughout the several views of the drawings.

Referring now more particularly to Fig. 1, there is shown by way of example at numeral 1, a locomotive wheel on the end of a journal 3. It 55 will be understood that in the case of a locomo-

tive, the journals are inside of the wheels, whereas in the case of passenger and freight cars, the journals are outside of the wheels. It will be understood that the invention is equally applicable to both classes of journals.

At numeral 5 is shown a journal box which fits into the pedestals of the locomotive frame. Within the journal box is carried a bearing 7, known in other classes of these structures as a "crown brass". From the above, it will be seen 10 that the load of the locomotive is transferred from the pedestals through the journal box 5 and crown brass 7 to the journal 3. The bearing is incomplete in kinematic form, leaving the underside of the journal exposed.

As will be shown hereinafter, the journal 3, while moving, is constantly flushed from the bottom with oil. In order that some of this oil may be in an advantageous position between the journal 3 and bearing 7 when the vehicle stops, I 20 provide the crown brass 7 with grooves of the nature shown in Figures 5 to 7.

Grooves 9 and 11 are formed as oppositely pointing arrow or T-heads having peripheral portions 13 and sloping branches 15 which, on 25 the cylindric surface of the crown brass, become helically arranged. The helical effect is not shown in Figure 5, because it would have to be exaggerated to become apparent. The peripheral portions 13 communicate with the flat bottomed surfaces 17 of the brass; whereas the ends 19 of branches 15 fall short of these surfaces 17 and are blind ended. The purpose of this particular grooving (grooves 9 and 11) is to provide the oil pick-up passages 13 which will receive a heavy supply of lubricant and carry it up to the junction 21 with branches 15. The junctions 21 will be seen to constitute the highest point in the grooves 9 and 11 when the crown brass is inverted and applied to the journal 3. 30 Hence the oil passes from the junction 21 by gravity down the branches 15. Thus the grooves 9 and 11 act as effective distributor grooves. Groove 9 or 11 is effective, depending upon which way the journal is rotating, backwards or forward.

When the journal stops, the lubricant at the junction 21 runs down the branches 15 to the end 19 where it is blocked and retained as a reservoir of lubricant for use immediately upon 50 starting. This is an advantage over other grooving systems used in conjunction with flushing devices in that said other devices permit the lubricant to run out of the bearing by gravity when the vehicle stops. Hence, under prior con- 55

ditions the static friction upon starting was excessive but this is avoided with the present invention. Two grooves 9 and 11 are used in order to obtain the described effect for either forward or rearward journal rotation.

5 A groove 23 is cut longitudinally of the partial cylinder formed by the crown brass and has for its purpose the wiping of lubricant which escapes from the grooves 9 or 11, said groove 23 10 distributing the lubricant laterally over the bearing area.

15 Endwise peripheral grooves 25 effect an outlet for lubricant which would otherwise tend to creep to the ends of the crown brass. The lubricant, upon reaching the outlet grooves 25, takes the form of a peripheral bead about the journal. This it could not do without grooves 25. Centrifugal force and gravity aid in forming the bead at the plane of each groove 25. Thus the 20 lubricant is carried downwardly upon the journal. It is displaced therefrom in a manner to be set forth hereinafter.

25 In order to effect said flushing with oil of the journal 3, I provide a sump 27 including a filling reservoir 28 having a capped inlet 30. This sump has upwardly extending walls 31 which lap longitudinal grooves 33 in the crown brass 7. The sump is supported by means of lips 35 resting upon ledges 37 of the journal box. 30 A metal dam 39, held to the journal box by means of bolts 41, carries a felt or the like wiper 43 for engagement with the journal. An upper dam 45 cooperates with said lower dam 39 (behind clips 47 welded to said dam 39) and is held 35 to the journal box by means of a bolt 49. It also carries a felt or the like, wiper 51. Numerals 53 indicate rivets for holding the felt wiper pieces.

40 At the other end, the sump 27 is provided with a wooden or like dam 55 normally pressed up against the journal 3 by means of a spring 57. By this means is formed the sump under 45 and around the ends of journal 3 for carrying lubricant which is flushed onto said journal.

45 Flushing is accomplished by pump P which will now be described in detail (Figs. 1, 3 and 4). The pump comprises a cylinder 59 having a head 61 which is welded at 63 to the sump 27. From the right-hand end (Fig. 3) of the cylinder 59 is introduced a reciprocating sleeve 65 having a renewable head 67 and a groove 69 with which 50 cooperates an outwardly pressing spring ring 71 for limiting the movement of the sleeve. The head 67 contacts with the hub of the locomotive wheel and responds by reciprocation in the cylinder 59 to lateral movement of the sump 27 with respect to the wheel. There is always such lateral movement between the sump and the wheel because of the side sway allowed between the journal box (to which is attached the sump) 55 and the wheels.

60 The interior of the head 67 contacts with, but is not joined to a plunger stem 75 which reaches to a plunger 77. The stem 75 carries a head 73. A spring 79 normally reacts on head 73 to cause 65 the plunger 77 to follow the motion of the head 67. The stem 75 is guided in a bushing 81 located in the end of a second cylinder 83 which carries said plunger 77. The cylinder 83 has a slip fit with respect to the cylinder 59 and is 70 provided with a dowel pin 85 which cooperates with a groove 87 in the cylinder 59 to effect a predetermined angular relationship between said cylinders 59 and 83.

75 The cylinder 83 carries an inlet check valve 89 and an outlet check valve 91, whereby recip-

ocation of the plunger 77 effects indrawing of the lubricant through the valve 89 and expulsion of the same through the valve 91.

From the valve 91, the lubricant is forced through a hollow stem 93 which is threaded to 5 the cylinder 83 the same having a clearing internal fit with respect to a cap 95, the latter serving in cooperation with the left-hand end of cylinder 59 to support a strainer 97 for straining the oil which proceeds to the downwardly located 10 check valve 89. The purpose of the predetermined angular relationship determined by the dowel pin 85 and recess 87 is to maintain the inlet check valve 89 directed downwardly to as 15 low a point as possible in the well of oil. 15

The hollow outlet 93 carries a shoulder 99 which cooperates with the manifold cap 95 to close the left end thereof. The closure 99 is provided with spanner wrench sockets 101 and a seat for a spring 103, the latter reacting against 20 the opposite end of the sump 27 to force together the parts 83 and 59, thereby maintaining the assembly of the pump in the sump.

Demounting of the pump for making repairs is quite simple. All that is necessary is to pull back 25 the spring 103 from the member 109. Thereafter parts 93, 95, 97 and 83 may be withdrawn from the support 59. The plunger 75 and spring 79 also are drawn out. These may then be readily separated by unloosening 99 and removing 81. 30 The head 67 with the sleeve 65 may be drawn out in the opposite direction. Repairs thus may be quite readily effected.

As shown in Figure 4, the outlet manifold 95 carries an outlet pipe 105 which has a slip fit 35 107 in a recess of a lubricant well 109 (see also Fig. 1).

The well 109 has a slidable applicator 111 which is normally spring pressed upwardly by means of spring 113, the applicator 111 having a 40 bearing on a stem 115 and limited in its motion by a cross pin 117. The applicator includes a spread head 119 for contacting with the journal 3.

45 It will be seen that as the side sway takes place with the motion of the vehicle, the pump P withdraws lubricant from the sump and forces it through the manifold 95, pipes 105, well 109, and applicator 111 against the journal 3. It will be seen that as the fluid presses through the 50 applicator, a reaction is set up which tends to displace the member 111 downwardly. This effects a spreading of the lubricant laterally over the journal 3.

55 The lubricant adheres to the journal (primarily in a central band) and is carried upwardly through the grooves described in connection with the crown brass 7. Here it is properly spread laterally. Any tendency to leak at the ends of the journal is substantially prevented by 60 the grooves 25 which form beads of the oil, the same being carried downwardly again on the journal. Beneath the grooves 25 but pressing against the journal are brass, bronze or similar wiper springs 120 held on brackets 121 for stripping the beaded lubricant from the journal and dropping it into the sump. It will be noted in this connection that the ends of grooves 25 65 communicate with the flat 17 of the crown brass 7, thus providing the desired outlets. More than 70 two grooves 25 may be used, if desired.

75 It will be understood that one or more pumps may be used within a given sump. For instance, in Figs. 8 and 9 are shown such. To pumps P1 and P2 are used with applicators A1 and A2 with 75

suitable passage to the same corresponding to that shown in the present described form. The spring 103 for retaining the pump assemblies react against brackets 123, instead of the end of the pump. This is because the pump is made longer so as to be applicable to a longer journal.

The longer crown brass required for the longer journal of this form of the invention is shown in Figure 9 wherein like numerals designate like parts. It will be understood that an applicator is placed beneath each set of peripheral grooves 13 of the grooves having the general appearance of arrow or T-heads. In this case a single set of endwise grooves 25, are again used because this is all that is necessary on any crown brass to prevent endwise leaking. The corresponding wiper springs 120 are also used.

It will be appreciated that any or all of the grooves above-described may be placed in communication with suitable reservoirs hollowed out of the crown brass itself or otherwise arranged.

It will be seen that one of the features of the invention is the provision of means for flushing an excess quantity of lubricant against the journal and then effectively recapturing the excess so as to effect a low lubricant consumption. The grooves 25 and the wipers 120 effect this recapture in connection with the formation of the described beads of lubricant. If it were not for this feature the oil would continue to travel along the journal to the wheel on one side, and along the axle on the other side, to be lost. Without this feature it would also probably be necessary, in order to obtain economical oil consumption, to use a pump with an adjustable stroke so as to cut down the consumption under excessive conditions of sway. With this invention maximum quantities can be pumped at all times without waste. This not only economizes on oil but simplifies the apparatus.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. In apparatus of the class described, a journal, a bearing upon the journal, said bearing having at least one groove formed to receive flushed oil which is carried upwardly on the journal and

to deliver the same upwardly, then back laterally and downwardly, said groove having a blind end.

2. In apparatus of the class described, a journal, a bearing supported on said journal, endwise peripheral grooves in said bearing, said grooves communicating with a space adjacent the lower side of said journal, stripper members engageable with the journal to strip lubricant from the same at points below said peripheral grooves, and at least one groove in said bearing adapted to receive lubricant, said last-named groove having a laterally arranged portion for distributing said lubricant downwardly after the same has been received in the groove, the downward portions of said last-named grooves having no communication with the sump.

3. In apparatus of the class described, a journal, an incomplete bearing on the upper side of said journal, said bearing having a groove adapted to receive flushed lubricant from said journal and advance it upwardly, at least one continuation in said groove adapted to carry said lubricant laterally and downwardly with a component of movement in a direction opposite the direction of oil advance and a dead end in said continuation.

4. In apparatus of the class described, a journal, an incomplete bearing on the upper side of said journal, said bearing having a groove adapted to receive lubricant and carry it upwardly, continuations in said groove adapted to carry said lubricant laterally and downwardly with a component of movement in the direction from whence the oil came, said continuations having dead ends, endwise peripheral grooves in said bearing communicating with the open spaces about the journal, strippers located in the planes of said last-named grooves adapted to strip gathered lubricant from the journal as determined by said peripheral grooves, and a laterally arranged spreader groove located adjacently to said first-named groove.

5. In apparatus of the class described, a journal, an incomplete bearing on the upper side of said journal leaving an open space adjacent the lower side of said journal, said bearing having at least one groove in free communication with said open space and adapted to receive oil which is carried upwardly on the journal and to deliver the same upwardly, then laterally and downwardly, said groove having a blind end blocking free access to said open space by lubricant in the groove.

FRANK S. BARKS. 55
